023-345

EX

07463

OP

261

Dec. 26 /

William P. Crepon, Assignee of Stuart, Crepon & Siebert, all of, Philadelphia, Pa.
Letters Patent No. 261 Dated Feb 5, 1850, antedated Oct 1, 149

uuuu.

The Schedule referred to in these Letters Patent and making part of the same

uuuuu

To whom it may concern:

Be it known that we, Wm. P. Crepon, David Stuart and Peter Siebert, all of the County of Philadelphia, in the State of Pennsylvania, have invented or produced a new and useful set of designs which are intended to ornament a stove called a Cottage Parlor air tight and do hereby declare that the following is a full and exact description of the same.

Fig. 1. Represents the hearth plate with leaves and scroll work on the outer edge as represented at a, a, a, a, terminating in the front with a leaf as at c.

Fig. 2. Represents the lower top beautifully carved on the outer edge with leaves and scroll work as at a, a, a, a.

Fig. 3. Represents the top plate carved in the centre with rosette as at a, around which you have scroll work as at b, b, on the outer edge you have leaves and scroll work as at c, c, c, c, -

Fig. 4. Represents the side plate very beautifully designed in the centre with leaves and scroll work as at a. a. a. a. on either side there is some very pretty scroll work as at b. b. b. b. outside of which you have a pretty scroll as at c. c. the whole side is divided off into Panels as at d. d. d. d. -

Des. 3681

2

Fig 5. Represents the end carved in centre with leaves and scroll work as at a. a. a. a. on either side you find scroll work at b. b. -

Fig 6. Represents the frame and fire doors the frame being beautifully carved on the outer edge with scroll work as represented at a. a. a. a. the doors are also ornamented with scroll work and beading as at b. b. b. b. -

Fig 7. Represents the draft door designed with rosette and scroll work as at a. a. a. -

Fig 8. is the foot very beautifully designed with scroll work and rosettes as at a. a. a. a. -

We have thus described the ornamental design which we claim as our invention or production and desire to secure by letters patent the design for a Stove called the Cottage Parlor air tight herein fully described and represented in the accompanying drawings.

Witnesses

John R. Sappington
Sam'l. H. Young

End

W.D.B.

Wm P. Copeon
David Stuart
Peter Leibert

540